UNITED STATES PATENT OFFICE.

JAMES R. FRYE, OF NEW PHILADELPHIA, OHIO.

DESIGN FOR A HANDLE FOR RASPS OR FILES.

SPECIFICATION forming part of Design No. 35,505, dated December 31, 1901.

Application filed November 13, 1901. Serial No. 82,162. Term of patent 3½ years.

To all whom it may concern:

Be it known that I, JAMES R. FRYE, a citizen of the United States, residing at New Philadelphia, in the county of Tuscarawas and State of Ohio, have invented and produced a new and useful Design for Handles for Rasps or Files, of which the following is a specification.

My invention relates to new and useful designs for handles for rasps or files, of which the following is a specification, reference being had to the accompanying drawings, forming a part thereof, in which—

Figure 1 is a perspective of my handle. Fig. 2 is a side elevation. Fig. 3 is an end elevation of the same.

The numeral 1 designates an elliptical uniformly-beveled grip which bears a reduced shank 2 at one end, having an enlarged head 3 formed on one side thereof. The head 3 is rounded off on the back at 4 and apertured

at 5. A rectangular aperture 7 traverses the head longitudinally, and a rounded face 8 is formed on the front thereof.

The essential or material features of my design are the elliptical beveled grip 1 and the reduced shank 2, bearing the enlarged head 3, formed on one side thereof and having a rectangular aperture therein.

Having described my invention, what I claim as new, and desire to secure by Letters Patent, is—

The design for a handle for rasps or files, substantially as shown and described.

In testimony whereof I have hereunto set my hand in presence of two subscribing witnesses.

JAMES R. FRYE.
